Application March 10, 1954, Serial No. 415,386

Claims priority, application Germany March 12, 1953

11 Claims. (Cl. 200—98)

The present invention relates to a combination switch for establishing electric connections of separate conductors.

It is an object of this invention to provide a combination switch which will be adapted to carry out the various commands given by a stepped switch or a preset control as it occurs for instance in connection with machine tools for machining workpieces.

It is a further object of this invention to provide a combination switch of the above mentioned character which will comprise a maximum of switch possibilities.

It is a still further object of this invention to provide a combination switch of the above mentioned type which will require a minimum of space.

Still another object of this invention consists in the provision of a combination switch as set forth above which will be simple in construction and safe in operation.

It is also an object of this invention to provide a combination switch of the above mentioned type which will have a minimum of conductors and soldering points and will be easy to check and easy to be operated.

These and other objects and advantages of the invention will appear more clearly from the following specification in connection with the accompanying drawings in which:

Fig. 1 is a perspective view of a portion of the combination switch according to the invention.

Fig. 2 illustrates the actuating magnets for the portion shown in Fig. 1 which latter contains the switch bridges.

Fig. 3 is an exploded view of a portion of Fig. 1 but on a scale larger than that used in Fig. 1.

Fig. 4 is a switch bridge with contact fingers as shown in Fig. 1.

Fig. 5 shows the structures of Figs. 1 and 2 in assembled condition.

Fig. 6a represents a contact bridge similar to that of Fig. 4 but with all tongues connected thereto.

Figs. 6b to 6d represent contact bridges similar to that of Fig. 4 but with different tongues removed.

General arrangement

According to the combination switch of the present invention, the conductors consist of parallelly extending metal bands. These metal bands are bent so as to form corrugated elements in which the legs of the corrugations form the contact points. The said corrugations are engaged by contact fingers which by displacement or tilting of the switch bridges interconnecting said contact fingers, contact the legs of said corrugations and thus establish electric connection of those conductors for which the contact fingers of the switch bridges are provided.

2

Structural arrangement

Referring to the drawing in detail, the combination switch according to the present invention comprises conductors in form of corrugated metal bands 1. The legs 1a and 1b of the corrugations form the contacts. The arrangement according to the invention furthermore comprises switch bridges generally designated 2 (Fig. 4) which in the particular embodiment shown in the drawings have a comb-like appearance with the teeth 3a, 3b, 3c, 3d serving as contact fingers. The metal bands are arranged along parallel lines and are insulated from each other by strips 4 arranged therebetween. The rows of metal bands 1 and insulating strips 4 are interconnected by means of insulating strips 5 and 6 extending transverse thereto. The said insulating strips 5 and 6 are arranged parallel to each other so that the entire arrangement has a honeycomb-like appearance. The insulating strips 5 extend through the corrugations arranged one behind the other in such a manner that one leg 1a of each of the corrugations of the metal bands 1 has its inside covered up by said insulating strips 5. In this way the contact finger 3 is prevented from resting against the leg 1a. In order to prevent an undesired contact of the contact fingers 3 with the legs 1b, the contact fingers 3 are resiliently pressed against the insulating strips 5 when the switch bridges 2 occupy their rest position. The insulating strips 6 extend between two adjacent corrugations of all metal bands 1 arranged one behind the other and hold together the metal bands 1 and insulating strips 4. The insulating strips 4 are provided with cut-outs 4a which serve as supports for the insulating strips 5 and 6.

The two extreme insulating strips 7 which confine that portion of the switch which comprises the metal bands 1 and insulating strips 4, 5 and 6 are thicker than the insulating strips 4 and extend downwardly so that their ends can be provided with wedge-like cut-outs 8 for receiving the switch bridges 2. Switch bridges 2 are provided with cut-outs 9 at their supporting points, which 40 cut-outs are engaged by insulating strips 7 in order to prevent the switch bridges 2 from lateral displacement. The insulating strips 5 and 6 are connected with the switch bridges 2 by means of tension springs 10 so as to maintain the insulating strips and switch bridges within 45 their respective supporting cut-outs.

The insulating strips 7 are interconnected and braced against each other by means of rods 11.

For purposes of actuating the switch bridges 2, each switch bridge has associated therewith a magnet 12 with a movable iron core 13 which latter moves out of said magnets when the latter are actuated. The magnets 12 are arranged in rows on a base plate 14 and are offset with regard to each other along oblique lines in order to save space. At the ends of the base plate 14 and perpendicular thereto are mounted two resilient plates 15. These plates 15 are connected to that part of the switch (henceforth called the upper part) which comprises the metal bands 1 and insulating strips 4, 5 and 6 etc. so that they form a parallelogram with the said upper part and the base plate 14. In view of the resiliency of the plates 15, the base plate 14 with the magnets 12 (henceforth called the lower part) can be displaced parallel with regard to the upper part.

When one of the magnets 12 is excited, its iron core 13 will move out of the respective magnet. When the upper part is moved parallel with regard to the lower part, the said core 13 abuts the tongue 2a of the switch bridge 2 pertaining thereto. When the upper part is moved fur-

ther with regard to the lower part of the switch, the core 13 presses against the tongue 2a so that the switch bridge 2 pertaining thereto is tilted about a line passing through the bearings or supports 9a. The parallel movement of the upper part with regard to the lower part can be effected in any desired manner for instance by means of a magnet.

Fig. 5 shows the structures of Figs. 1 and 2 in assembled condition. As will be seen from Fig. 5, when assembling the structures of Figs. 1 and 2, the upper edges of the metal plates 15 engage corresponding slots 11a in the two bolts 11 of the upper part shown in Fig. 1. The upper and lower part are held together by two springs 17. One end of spring 17 passes around the bolt 11 and, in order not to impede the end portion of this spring, the plate 15 is provided with a notch 15a. The other end of the spring 17 engages a pin 18 on the lower part shown in Fig. 2. The two springs 17 in addition to holding the upper and lower parts together bring about that both parts when moved relative to each other while the resilient plates 15 bend, will return to their starting or normal position when the force bringing about said relative movement subsides. The individual conductors connected to the metal bands 1 and adapted selectively to be electrically interconnected by the switch are designated with the reference numeral 24. The feeding lines to the magnets 12 are designated with the reference numeral 25 and are connected to the lower portion thereof.

The switch bridge shown in Fig. 6a corresponds substantially to that of Fig. 4. However, while in Fig. 4 the tongue-like contact members 3a, 3b, 3c and 3d only are shown in full lines, Fig. 6a shows all of the contact members 19, 20, 21, 22 and 23 in full lines, which means that the contact member of Fig. 6a has all of its contacting tongues connected thereto, whereas in the switch bridge of Fig. 4, many of the contact members have been removed. When a switch bridge according to Fig. 6a is actuated by causing the magnetic core 13 to be lifted in front of the tongue 2a while the upper part of the switch is moved relative to the lower part, all metal bands 1c to 1g, and thus all conductors 24 will be electrically interconnected.

If, however, a switch bridge according to Fig. 6b is employed or actuated which has the contact fingers 20, 22, 23 removed, it will be evident that only the two metal bands 1c and 1e will be electrically interconnected. Correspondingly, a switch bridge according to Fig. 6c will, when actuated, electrically interconnect the metal bands 1c, 1e and 1f only.

Operation

In the rest position, the switch bridges 2 have their contact fingers 3 in resilient contact with the insulating strips 5 in order safely to prevent a contact and thus an electric connection with the legs 1b of the corrugations. The resiliency is obtained by bending out one or more contact fingers at each switch bridge. The bent-out contact finger rests against the leg 1b of one metal band, and all bent-out fingers of all switch bridges rest against the same metal band. This metal band is either always currentless or it acts as neutral wire, i. e. in each combination position, the connection of the respective metal bands 1 is to be effected with this neutral wire.

The control combs are, for purposes of simplicity, provided with as many teeth as there are metal bands 1. Those teeth which are not necessary for the combination to be controlled are removed from each control comb. These teeth are indicated in Fig. 4 by dot-dash lines. In order to bring about a desired combination which as stated is pre-set on a switch bridge, the magnet 12a (Fig. 2) which is associated with this switch bridge receives current and thereupon moves its core 13a upwardly. When parallelly displacing the upper part with regard to the lower part of the switch, the core 13a presses against the abutment 2a of the switch bridge pertaining thereto

in such a manner that the contact fingers thereof rest against the legs of the corrugations of those metal bands 1 which pertain to the desired combination.

The wedge-shaped form of the cut-outs 8 allows a tilting movement of the switch bridges 2 and simultaneously limits said switch movement so that an overload of the contact fingers 3 and thus a deformation will be prevented.

In addition to the simple easy to be checked design of the present invention which requires only a minimum of space, another important advantage of the switch according to the invention consists in that the power which brings about the contact pressure does not have to be produced by the magnet through which the control currents pass. The said force is rather produced by one single powerful magnet for the total of all circuits. It is this magnet which brings about the relative parallel displacement of the two parts of the switch. In this way, the control output requires only a small amount of energy.

It is, of course, understood that the present invention is, by no means, limited to the particular constructions shown in the drawings but also comprises any modifications within the scope of the appended claims.

What I claim is:

1. A combination switch comprising in combination: a plurality of metal bands normally insulated from each other and bent so as to have a corrugated contour formed by U-shaped cranks having plane surfaces and being alternately directed in opposite directions while the legs of each of said cranks of each metal band are respectively common to the respective adjacent cranks, one leg of each of said cranks of each metal band forming a plane contact surface, said bands being arranged substantially parallel to each other and forming electric conductors, a plurality of comb-like contact bridges having plane surface teeth-like contact fingers respectively extending into cranks of a plurality of said bands, each of said contact bridges being tiltable about a line parallel to the longitudinal axis of said contact bridges from an ineffective position in which said fingers are spaced from the respective adjacent contact surfaces into an effective position for engaging said contact surfaces by said fingers, the number of contact fingers of said contact bridges corresponding only to the number of cranks the contact surfaces of which are to be engaged for establishing desired circuits, and means arranged for tilting said contact bridges to bring about the respective contact of said contact bridges with the adjacent contact surfaces of said metal bands.

2. In a combination switch: a plurality of metal bands normally insulated from each other and bent so as to have a corrugated contour formed by U-shaped cranks having plane surfaces and being alternately directed in opposite directions while the legs of each of said cranks of each metal band are respectively common to the respective adjacent cranks, one leg of each of said cranks of each metal band forming a plane contact surface, said bands being arranged substantially parallel to each other and forming electric conductors, a plurality of contact bridges having plane surface contact fingers extending into cranks of a plurality of said bands and also being provided with abutment means, said contact bridges being movable selectively from an ineffective position in which said fingers are spaced from the respective adjacent contact surfaces to an effective position for causing said fingers to engage said contact surfaces to thereby establish desired circuits, a plurality of magnets with a movable core therein, the number of said magnets and cores corresponding to the number of said contact bridges, each of said contact bridges having associated therewith a magnet with a movable core therein adapted in response to current passing through said magnet to move out of the respective magnet and while in moved out position in response to a relative movement between said magnets and said metal bands and contact bridges to

cause the latter to move the contact fingers of the respective adjacent contact bridge into effective position.

3. A combination switch according to claim 2, in which the magnets and the abutment means cooperating therewith are laterally offset in the direction of the contact bridges.

4. In a combination switch: a plurality of metal bands normally insulated from each other and bent so as to have a corrugated contour formed by U-shaped cranks having plane surfaces and being alternately directed in opposite directions while the legs of each of said cranks of each metal band are respectively common to the respective adjacent cranks, one leg of each of said cranks of each metal band forming a plane contact surface, said bands being arranged substantially parallel to each other and forming electric conductors and contacts, a plurality of contact bridges having contact fingers extending into cranks of a plurality of said bands, said contact bridges being movable selectively from an ineffective position in which said fingers are spaced from the respective adjacent contact surfaces to an effective position for causing said fingers to engage said contact surfaces to thereby establish desired circuits, said metal bands and said contact bridges forming a first unit, a plurality of magnets with cores therein movable out of said magnets in response to current passing therethrough for actuating said contact bridges, said magnets and cores forming a second unit and while corresponding in number to the number of movable contact bridges being respectively arranged for cooperation with said contact bridges, said two units being movably arranged with regard to each other, and control magnet means operable to effect a relative movement of one unit with regard to the other unit to thereby cause the cores of the respective magnets receiving current to actuate the respective adjacent contact bridges to move their contact fingers into effective position.

5. In a combination switch: a plurality of metal bands normally insulated from each other and bent so as to have a corrugated contour with alternating relatively narrow and wide U-shaped cranks open toward opposite sides and having plane surfaces while the legs of each of said cranks of each of said metal bands are respectively common to the respective adjacent cranks of one and the same band, one leg of each of said cranks of each metal band forming a plane contact surface on the inside of the respective U-shaped crank, said bands being arranged substantially parallel to each other and forming electric conductors and electric contact surfaces while the respective narrow and wide U-shaped cranks are in substantial alignment with each other, strips of insulating material arranged substantially parallel to each other and respectively engaging the inner leg surfaces of the wide U-shaped cranks other than said contact surfaces, a plurality of contact bridges having plane surface contact fingers respectively extending into a plurality of the wide U-shaped cranks of said bands, said contact bridges being movable selectively from an ineffective position in which said fingers are spaced from the respective contact surface opposite the surface engaged by the adjacent strip of insulating material to an effective position for causing said fingers respectively to engage said contact surfaces to thereby establish desired circuits, and yielding means yieldably pressing said contact fingers against the adjacent strip of insulating material when said contact fingers are in their ineffective position.

6. A combination switch according to claim 5, which includes an additional corrugated band corresponding in shape to said metal bands, and in which the yielding means of all of said contact bridges are arranged in the corrugations of said additional corrugated band and are formed by teeth-like prongs supported by said contact bridges, said additional corrugated band being arranged outside the circuits to be established by said switch.

7. A combination switch according to claim 5, which

includes an additional corrugated metal band corresponding in shape to said metal bands, and in which the yielding means of all of said contact bridges are arranged in the corrugations of said additional corrugated band and are formed by teeth-like prongs supported by said contact bridges, said additional metal band serving as neutral conductor in the circuits to be established by the switch.

8. In a combination switch: a plurality of metal bands bent so as to have a corrugated contour with alternating 10 relatively narrow and wide corrugations open toward opposite sides and having plane surfaces while the legs of each of said cranks of each of said metal bands are respectively common to the respective adjacent cranks of one and the same band, one leg of each of said cranks of each metal band forming a plane contact surface on the inside of the respective U-shaped crank, said bands being arranged substantially parallel to each other and forming electric conductors and electric contact surfaces while the respective narrow and wide corrugations are in substantial alignment with each other, strips of insulating material arranged substantially parallel to each other and respectively engaging one leg surface of the wide U-shaped cranks other than said contact surfaces, additional insulating strips arranged substantially parallel to 20 said metal bands and respectively insulating said metal bands from each other, said additional insulating strips being provided with cut-outs receiving said first mentioned insulating strips, a plurality of contact bridges having plane surface contact fingers respectively extending 25 into the wide U-shaped cranks of said bands, said contact bridges being movable selectively from an ineffective position in which said fingers are spaced from the respective contact surfaces to an effective position for causing said fingers to engage said contact surfaces to thereby 30 establish desired circuits, and yielding means yieldably pressing said contact fingers against the adjacent strip of insulating material when said contact fingers are in their ineffective position.

9. A combination switch according to claim 8, which 40 includes a pair of third insulating strips laterally confining that portion of the switch which contains the metal bands, said third insulating strips being thicker than said additional insulating strips and protruding beyond said portion and being provided with V-shaped notches in 45 which said contact bridges are tiltably journaled, the inclined surfaces of said notches limiting the tilting movement of said contact bridges.

10. In a combination switch: a plurality of metal bands having a corrugated contour with alternating relatively narrow and wide U-shaped cranks respectively open 50 toward opposite sides and having plane surfaces while the legs of each of said cranks of each of said metal bands are respectively common to the respective adjacent cranks of one and the same band, one leg of each of said cranks of each metal band forming a plane contact surface on the inside of the respective U-shaped crank, said bands being arranged substantially parallel to each other and forming electric conductors and electric contact surfaces, the relatively wide and narrow U-shaped 55 cranks of said bands respectively being in substantial alignment with each other, first strips of insulating material arranged substantially parallel to each other and respectively engaging one inner surface of the relatively wide U-shaped cranks other than said contact surfaces, second strips of insulating material arranged substantially parallel to each other and to said first strips of insulating material and respectively arranged in said relatively narrow U-shaped cranks while engaging the sides thereof adjacent the respective nearest first strip of insulating material to maintain said metal bands in their respective 60 positions, a plurality of contact bridges having contact fingers extending into the wide U-shaped cranks of said bands, contact bridges being movable selectively from an ineffective position in which said fingers are spaced from the respective contact surface to an effective position for

causing said fingers to engage said contact surfaces to thereby establish desired circuits, and yielding means yieldably pressing said contact fingers against the adjacent first strip of insulating material when said contact fingers are in their ineffective position.

11. A combination switch according to claim 10, which includes spring means yieldably connecting said first and second strips of insulating material with the respective adjacent contact bridges.
